(57) **CLAIM**

The ornamental design for an pressing tool, as shown and described.

DESCRIPTION

FIG. 1 is a front perspective view of an embodiment of a pressing tool;

FIG. 2 is a rear perspective view of the pressing tool of FIG. 1;

FIG. 3 is a first side elevational view of the pressing tool of FIG. 1;

FIG. 4 is a second side elevational view of the pressing tool of FIG. 1;

FIG. 5 is a rear end view of the pressing tool of FIG. 1;

FIG. 6 is a front end view of the pressing tool of FIG. 1;

FIG. 7 is a top view of the pressing tool of FIG. 1; and,

FIG. 8 is a bottom view of the pressing tool of FIG. 1. The broken lines in the figures illustrate portions of the pressing tool but form no part of the claimed design.
